Primary Examiner — Richard Kearney*Assistant Examiner* — Anthony Vincent Rotolo(74) *Attorney, Agent, or Firm* — Stetina Brunda Garred & Brucker(57) **CLAIM**

The ornamental design for a track light as shown and described.

DESCRIPTION

FIG. 1 is a front perspective view of the track light of the present invention showing my new design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The portions of FIGS. 1-6 shown in broken lines do not form any part of the claimed design.

1 Claim, 7 Drawing Sheets(56)
